UNITED STATES PATENT OFFICE.

RICHARD FLEMING AND CROMWELL A. B. HALVORSON, JR., OF LYNN, MASSACHUSETTS,
ASSIGNORS TO GENERAL ELECTRIC COMPANY, A CORPORATION OF NEW YORK.

ARC-LAMP.

964,691.

Specification of Letters Patent. Patented July 19, 1910.

Application filed January 16, 1906. Serial No. 296,304.

To all whom it may concern:

Be it known that we, RICHARD FLEMING and CROMWELL A. B. HALVORSON, Jr., citizens of the United States, residing at Lynn, 5 county of Essex, State of Massachusetts, have invented certain new and useful Improvements in Arc-Lamps, of which the following is a specification.

Our present invention relates to arc lamps in which the character of the electrodes employed is such that a flaming or luminous arc is obtained. In such lamps the major portion of the illumination comes 10 not from the tips of the arcing electrodes heated to incandescence as in the ordinary carbon arc lamp, but from the arcs between the electrodes. The increased length of such arcs, the comparative slowness with which the electrodes which produce them are con- 15 sumed if the electrodes are suitably chosen, and other differences between luminous arcs and the ordinary carbon arc render it desirable to employ feeding mechanisms for the electrodes in these lamps differing from 20 those heretofore employed with lamps employing carbon electrodes.

With the electrodes employed for the production of luminous or flaming arcs the arc products are not practically all permanent 25 gases as in the case of carbon electrodes, but on the contrary contain much matter which condenses to a solid form when cooled to a temperature approaching that of the atmosphere. On this account it is necessary 30 to provide means for disposing of the arc products.

Our present invention comprises certain 35 features of construction and arrangement, particularly of electrode feeding mechanisms and smoke or fume disposing means particularly adapted for use in luminous or flaming arc lamps, though some of them are not exclusively limited to such use.

The various features of novelty which 40 characterize our invention are pointed out with particularity in the claims annexed to and forming a part of this specification.

For a better understanding of our invention and the advantages possessed by it, reference may be had to the accompanying 45 drawings and descriptive matter in which we have illustrated and described one of the forms in which our invention may be embodied.

50 Of the drawings, Figure 1 is a perspective

view of an arc lamp with the casing in section; Fig. 2 is an elevation of a portion of a globe holder; Fig. 3 is an elevation on a larger scale than Fig. 1 showing the clutch mechanism in the position occupied at the instant of starting the arc; Fig. 4 is a diagram illustrating the circuit arrangements and the position of the feeding mechanism at the instant at which the electrodes are in contact; Fig. 5 is a perspective view illustrating the clutch mechanism of Figs. 1, 3 and 4; Fig. 6 is a sectional elevation illustrating the arrangement of the upper electrode and the hood or fuse box surrounding it; Fig. 7 is an elevation illustrating a modified form of clutch mechanism in the normal working and out of service position; and Fig. 8 is a plan view on the line 8-8 of Fig. 7.

In the drawings, 1 represents a tubular 5 member which forms the backbone of the arc lamp structure and serves as a chimney through which the arc products pass. This member may be one integral mechanical element or may be formed in sections. A 10 flat disk like hood or shield 2 is secured above the end of the chimney proper by arms 3. Bracket arms 4 extending from the upper side of the hood form a means by which the lamp may be supported. The 15 feeding mechanism of the lamp is located between a hood or platform 5 secured to and surrounding the chimney 1 near its upper end and a platform 6 secured to and surrounding the member 1 at or near its lower 20 end. The lamp mechanism located between the platforms 5 and 6 is inclosed by a suitable casing 5' which may be of any well known form.

To the lower end of the member 1 is secured in any suitable manner a bell shaped hood or member 7. The member 7 has an opening in its upper end which communicates with the interior of the chimney member 1. A hollow tubular member 8 is supported in the member 7 in line with the chimney 1 by means of a hollow support 9 which in the form shown is integral with the member 8 and the hood proper. In the construction illustrated, the lower end of the member 8 projects some distance below the lower end of the hood proper.

The upper electrode 10 of the lamp is secured within the hollow member 8 with its lower end projecting slightly below the 110

2

lower end of the member. The lamp shown is intended for direct current operation and the upper and positive electrode 10 consists of a bar or rod of copper or similar material not readily oxidized and having good heat and electrical conductivity. The electrode 10 is secured in place by means of a threaded extension 11 which may be integral or separately connected thereto and which passes through the extension of the hollow supports 9 which close the upper end of the member 8 and engages a nut 12. In the construction shown the electrode 10 is insulated from the member 7. The external diameter of the electrode 10 is less than the internal diameter of the member 8, consequently an annular space 13 is formed between the electrode 10 and the member 8. The two portions of the hollow support 9 which extend from the member 8 to the member 7 proper, form conduits terminating in orifices 15 at the outer surface of the member 7 for establishing communication between the space 13 and the outside atmosphere.

25 The lower and negative electrode 16 of the lamp, which may be formed of or contain material such as titanium oxid, magnetic oxid of iron, titanium carbide or the like giving a flaming or luminous arc is supported in a socket formed in an arm 17, secured to the lower end of a tubular member 18, which in the construction illustrated is square in cross-section configuration. The member 18 which slides on a guide-rod 18' passes upward through apertures formed for the purpose in the member 7 and platform 6 where it is engaged by the clutch mechanism of the lamp.

30 The clutch mechanism of the lamp really includes two separate clutching devices which engage the member 18. Of these, in the construction illustrated, the lower clutching device which we may call an arc length limiting clutch comprises a member 19 formed of stamped metal having an aperture 20 formed at one end to receive the member 18. While the member 19 is substantially horizontal throughout the greater portion of its length, it will be observed that 35 the portions surrounding the aperture 20 are inclined to the member 18 so that the portion 21 of the clutch which engages the outer corner of the member 18 is below the portion 22 of the member 19 engaging the diametrically opposed corner of the member 18. In the position of the lamp mechanism shown in Fig. 1, the end of the member 19 remote from the member 18 rests upon a stop 23 secured to the platform 6 and the 40 member 18 is gripped between the portions 20 and 21. A stop member 24 provided with a hook 25 at its upper end and having a slot 26 formed in it (Fig. 5) is adjustably secured to the stop 23 by a screw 27. The 45 vertical portion of the stop 24 passes through

an opening formed for the purpose in the member 19. It will be understood that while the member 19 can move along the vertical portion of the stop 24, the upward movement of the member 19 is limited by its engagement with the portion 25.

The upper clutching device or member 28 which we may call the actuating clutch is pivotally connected to a lever like member 29 by a cotter pin 30. The members 28 and 29 in the form shown are made of stamped sheet metal. The member 28 is provided with an aperture 31 through which the member 18 passes. The portion 32 of the wall of this aperture engaging the outer corner of the member 18 is lower than the portion 33 of the wall engaging the opposite corner. A link member 34 has one end pivotally connected to the end of the member 29 remote from the member 28 by a cotter pin 35 and its other end pivotally connected to the member 19 by a cotter pin 36. Each of the members 19 and 29 is formed with an aperture through which passes the movable shell member 37 of a dashpot. The co-operating stationary piston member 38 of the dashpot is secured to the platform 6. The upper end of the member 37 is connected to but insulated from the yoke portion 39 of a U-shaped core, each of the legs 40 of which are axially movable into the corresponding one of two similar tubular magnetizing coils 41. A bracket 42 secured to the upper end of the member 37 is provided with two posts located one on each side of the member 37. The upper ends of the posts 43 are rounded to enter indentations 44 formed in the under sides of the portions of the member 29 at opposite sides of the member 37. To prevent lateral displacement of the member 29 a guide plate 45 is secured to the outside of each post 43 by screws 46.

In Fig. 4 we have illustrated diagrammatically circuit arrangements which may be employed when it is desired to operate the lamp in a constant current circuit. In the diagram 50 and 51 represent the positive and negative terminals respectively of the lamp. A conductor 52 connects one terminal of the winding of a magnetizing coil 53 to the lamp terminal 51. The other terminal of the magnetizing coil 53 is connected to the positive electrode 10 of the lamp by a conductor 54. An armature 55 cooperating with the magnetizing coil 53 carries a contact 56. When the winding 53 is deenergized the contact 56 rests upon a co-operating contact 57 carried by a movable armature 58 cooperating with a magnetizing coil 59. The contact member 57 is connected to one terminal 60 of a resistance conductor 61, the other terminal of which is connected to the lamp terminal 51. One terminal of the coil 59 is connected to the terminal 60. The other terminal of the coil 59 is connect-

ed to one terminal of the coils 41, which are in series with each other. The other terminal of the coils 41 is connected to the lamp terminal 50. A conductor 61 connects the 5 negative lamp terminal 50 to the electrode 16. It will be observed that the coil 50 is in shunt to the electrodes, while the coil 53 is in series with them. When the coils 53 and 59 are both deenergized the contacts 56 and 57 are in contact. When the coil 53 is energized and the coil 59 is not operatively energized the member 56 is held out of engagement with the member 57. When the coil 53 is energized and the coil 59 is also energized by the passage of a sufficiently large current through its winding, the contacts 57 will be moved into engagement with the contact 56.

Fig. 1 shows the lamp mechanism in the position occupied by it when the lamp is out of circuit and also when in normal operation. In this position the electrode 16 is supported from the stop 23 through the members 18 and 19. The outer end of the member 28 then rests on the outer end of the member 19. The inner end of the member 28 being carried down by the member 29 so that the member 28 is not locked to the member 18. When the lamp is out of circuit the coils 41, 53 and 59 are all deenergized. As soon as the lamp is connected into circuit current begins to flow through the coils 41 between the terminals 50 and 51 through a circuit including resistance 61 and contacts 56 and 57, and windings of the coils 41. This energizes the coils 41 and causes them to attract the armature 39. When the armature 39 is moved upward by the coils 41 after a slight initial upward movement of the end of the member 28 connected to the member 29 sufficient to cause the member 28 to lock itself to the member 18, the two clutches and the member 18 move upward together until the member 19 engages the hook 25. Further upward movement of the armature will cause the member 19 to turn in the direction indicated by the lower arrow in Fig. 3. A very slight movement of the member 19 is sufficient to cause 45 a disengagement between it and the member 18, after which the member 19 remains stationary until the member 18 starts to descend. Since the lower end of the link 34 is held stationary while the member 19 is 50 in engagement with the hook 25, further upward movement of the armature 39 causes the lever member 29 to turn about the cotter pin 35 in the direction indicated by the upper arrow causing the member 18 to be 55 elevated still further by the clutch member 28. While the clutch members move upward together the armature 39 and the member 18 will move at the same rate, but after the member 19 has stopped the upward movement of the member 18 will be more rapid

than the upward movement of the armature. As soon as the electrode 16 is moved into engagement with the electrode 10 further upward movement of the member 18 is stopped. The passage of current through the circuit including the electrodes then energizes the winding 53 and separates the contacts 56 and 57. This effectually deenergizes the windings 41 since the resistance of the conductor 62 and winding 59 is great enough to prevent a flow of current through the windings 41 sufficient to maintain the attraction of the armature 39. As soon as the contacts 56 and 57 are separated in the manner described, the armature 39 and member 18 start to move downward under the action of gravity. The dashpot members 37 and 38 are arranged to retard this downward movement so that the arc will be properly drawn between the electrodes. As soon as the member 18 starts to descend it is gripped by the member 19 whereupon the members 18 and 19 descend together. When the member 19 engages the stop 23 the downward movement of the member 18 and electrode 16 is checked. Further downward movement of the armature 39 results in causing the member 28 to drop into engagement with the member 19. It will thus be observed that after each feeding operation the arc struck is of a length equal to the play of the member 19 between the hook 25 and the stop 23. This can be adjusted by adjusting the member 24 with respect to the member 23. After the arc is struck in the manner described the lamp mechanism remains stationary until the rise in voltage of the arc due to its increase in length consequent upon the consumption of the lower electrode or from other causes, increases beyond a predetermined amount. When this occurs the coil 59 becomes energized sufficiently to move the contact 57 into engagement with the contact 56. This again energizes the windings 41 whereupon the feeding operation hereinbefore described is repeated. It will be understood that the parts are so proportioned that the movement of the member 18 through the member 19 at each feeding operation is sufficient to compensate for the electrode consumption occurring since the previous feeding operation, thus insuring that the lower electrode will be moved into contact with the upper electrode whenever necessary.

A projection 70 from the member 7 supports a rod 71 having an outturned portion 72 at its lower end. A bracket-like projection 73 on the member 7 diametrically opposed to the projection 70 has pivoted to it 125 a latch member comprising a rod 74 supporting at its lower end a ball 75. A transparent or translucent globe for inclosing the movable mechanism of the lamp located below the member 7 is supported through a 130

member 76. The member 76 comprises a girdle portion 77 which may be adjustably clamped about the globe by means of a screw 78. The ends of a resilient arc shaped member 79 are secured to the girdle at points separated somewhat less than 180°. Another arc shaped resilient member 80 diametrically opposed to the member 79 also has its ends secured to the girdle. The member 80 is substantially similar to the member 79, though in the form illustrated the member 79 is made of strips of metal while the member 80 is made of two similar pieces or strips of metal which are connected together by pins or rivets 81. As shown, the pins or rivets 81 are at different levels, the outer pin being slightly below the inner pin. These pins form the jaws of a clutch for engaging the rod 71. Pins or posts 82 diametrically opposed to the pins or rivets 81 are carried by the member 79. The pins 82 are adapted to straddle the member 74 and rests upon the ball 75.

It will be understood that in the position shown in Fig. 1 the upper end of the globe is held against the portion 7' (Fig. 6) of the lower end of the member 7. Downward movement of the right hand side of the globe is prevented by the engagement of the post 82 with the ball 75 and downward movement of the left hand side of the globe is prevented by the engagement of the pins 81 with the rod 71. When it is desired to remove the globe in order to trim the lamp or the like, the ball 75 is swung out whereupon the globe may be moved downward on the rod 71 until the portion 72 is reached. A cotter pin 83 ordinarily prevents the globe from being moved out of engagement with the rod 71. After the globe is lowered it may be swung sidewise about the portion 72 of the rod 71 as a pivot to allow replacement of the electrode 16 or other operation which it is desired to perform. The flexibility of the members 79 and 80 permits the globe to be readily adjusted against the member 7 to make a tight joint. When the globe is in the working position as shown in Fig. 1, air enters the arc inclosing chamber through the hollow support 9 and space 13. By bringing the air into the arc inclosing chamber in the form of an annular stream surrounding the positive electrode, not only is the positive electrode cooled by the incoming air, but the moving tubular body of air tends to position the arc and make it more stable. The heated air and products of combustion of the lower electrode are carried out of the arc chamber through the chimney member 1 through which a relatively powerful draft is created. It has been found that the hood member 2 arranged and proportioned as shown in Fig. 1 serves to prevent the air and gas flow through the chimney 1 from being disturbed

by variable winds. The upward flow of air by the lower electrode produced by the arrangement shown also serves to cool it and steady the lower end of the arc.

The clutch mechanism illustrated in Fig. 7 is similar in its general arrangement to that previously described, though differing in mechanical details of construction, and also in the addition of a spring which supplements the action of gravity in normally tending to hold the lower clutch member in locked engagement with the electrode carrying member. Referring to Fig. 7, a member 29' is connected by a cotter pin 84 to the movable dash pot member which as in the form of our invention previously described is mechanically connected to the armature of the feeding magnet. To the other and shorter end of the member 29' is pivoted the upper end of a substantially vertical connecting bar or member 85. To the lower end of the connecting bar 85 is pivoted by means of a cotter pin the upper clutch member 28'. To the longer end of the member 29' is pivoted the upper end of a link or member 34'. The lower clutch member 19' is pivotally connected to the lower end of the member 34'. The member 34' is provided with an extension 86 into which is hooked the upper end of a helical tension spring 87. The lower end of the tension spring is hooked into a screw 88 threaded into an opening formed for the purpose in the end of the bar 19' remote from the member 18 which is extended beyond the pivotal point of connection to the member 34'. The lower dashpot member is formed with the lower fixed stop for the member 19' and has adjustably secured to it a plate 24' provided at its upper end with a shoulder 25' which forms a stop for limiting the upward movement of the member 19'.

The operation of the form of our invention shown in Fig. 7 is substantially like that shown in the other figures of the drawings, though the flexible connection between the upper and lower clutches formed by the members 29' and 34' and the spring 87 insures at all times a smoother action of the electrode feeding mechanism than may always be had with the other form of our invention. It will of course be understood that the spring supplements the action of gravity in always holding the clutch member 19' in the position in which it tends to lock itself to the member 18.

Certain novel features described and illustrated but not claimed herein are specifically claimed in our copending applications Serial Numbers 181,332, and 248,549, filed Nov. 16, 1903, and March 6, 1905, respectively.

While the forms of our invention hereinbefore described and illustrated have been

- found to give excellent results in practice, it will be understood by all those skilled in the art that changes may be made in the embodiments of our invention without departing from its spirit, and we do not wish the claims hereinafter made to be limited to the particular embodiments disclosed more than is made necessary by the state of the art.
10. What we claim as new and desire to secure by Letters Patent of the United States, is:
1. In an arc lamp, a movable electrode, a member moving with the electrode, two clutches engaging said member, one of said clutches being pivotally connected to the other some distance from the member, and a member for moving said clutches pivotally connected to said other clutch at a point between the member and the point of connection with the other clutch.
  2. In an arc lamp, a movable electrode, a member moving with the electrode, a clutch having a portion engaging the member and another portion extending away from the member, a second clutch connected to the first at a portion remote from the member, means for moving said clutch engaging the first mentioned clutch between the member and the point of connection with the other clutch.
  3. In an arc lamp, a movable member, an actuating device, a lever pivoted to the actuating device, and a pair of clutch members mechanically connected to the lever, one at each side of the point of connection of the lever to the actuating device, each of said clutch members engaging said movable member.
  4. In an arc lamp, a movable member, an actuating device, a lever pivoted to the actuating device, a pair of clutch members mechanically connected to the lever one at each side of the point of connection of the lever to the actuating device, each of said clutch members engaging said movable member, and stops limiting the movement of one of said clutch members.
  5. In an arc lamp, a movable member, an actuating device for moving the member in one direction against the action of a force constantly tending to move the member in the opposite direction, a lever pivoted to the device, and a pair of clutches each engaging said member, connections between them and the lever, the connections between said lever and one of said clutches being such as to normally hold that clutch in the position in which it is locked to the member.
  6. In an arc lamp, a movable member, an actuating device for moving the member in one direction against the action of force constantly tending to move the member in the other direction, a lever pivoted to the device, a pair of clutches connected to the lever

each engaging said member, the connections between said lever and one of said clutches being such as to normally hold that clutch in the position in which it is locked to the member, and stops limiting the movement of that clutch.

7. In an arc lamp, a movable electrode, a coöperating electrode, an electro-magnetic actuating device provided with an armature, an actuating clutch connection between it and said armature, an arc length limiting clutch, a flexible connection between it and the armature, and stops limiting the movement of said arc length limiting clutch, said connections being arranged to cause said clutches to move together when the electrode is being moved toward the coöperating electrode until said arc length limiting clutch engages the stop limiting its movement in that direction.

8. In an arc lamp, a movable electrode, an actuating clutch for moving said electrode in one direction, a second clutch for limiting the extent of movement of the member in the opposite direction, and means mechanically connecting said clutches together.

9. In an arc lamp, an electrode carrying member, an actuating clutch therefor adapted to engage said member to move it in one direction, a second clutch for limiting the extent of movement of the member in the opposite direction, and means mechanically coupling together said clutches.

10. In an arc lamp, a member to be actuated, an actuating clutch engaging said member, means for moving said clutch and thereby said member, a second clutch also engaging said member, flexible means connecting said clutches, said means normally tending to cause said clutches to move together, and stops limiting the movement of said second clutch.

11. In an arc lamp, a movable electrode, a feeding mechanism therefor comprising two clutches, an electromagnet having a movable armature, flexible mechanical connections between said armature and each of said clutches, and stops controlling the movements of one of said clutches, said flexible connections being arranged to hold said stop controlled clutch in a fixed relation with respect to said electrode at all times except when in engagement with one only of said stops.

12. In an arc lamp, an electrode, clutching means for moving it in one direction against the action of a force opposing said movement, an arc length limiting clutch, an electromagnet having a movable armature, flexible mechanical connections between said armature and each of said clutches, and a stop limiting the movement of said arc length limiting clutch, said connections being arranged to normally hold the arc length lim-

iting clutch in fixed relation to said electrode, and to cause said clutches to move together when the electrode is moved against the action of gravity until the arc length 5 limiting clutch engages said stop and thereafter permitting relative movement between the clutches.

13. In an arc lamp, a chimney, a hood supported at the lower end thereof, a hollow 10 member supported by the hood with its axis in line with the axis of said chimney, and a conduit establishing communication between the space within said hood and the interior of said hollow member, said conduit 15 being integral with the hood and said member.

14. In an arc lamp, a chimney, a hood secured near the lower end thereof, a hollow

member supported by the hood with its axis in line with the axis of said chimney, a metallic non-consuming positive electrode secured in but not filling the space in said hollow member, a coöperating negative electrode, and a conduit establishing communication between the space within said hood and the interior of said hollow member, said conduit being integral with the hood and said member. 20 25

In witness whereof we hereunto set our hands this thirteenth day of January, 1906. 30
